UNITED STATES PATENT OFFICE.

ELUE O. FRITCH, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A TIRE-TREAD.

50,190.

Specification for Design.

Patented Jan. 16, 1917.

Application filed September 30, 1916. Serial No. 123,185. Term of patent 14 years.

To all whom it may concern:

Be it known that I, ELUE O. FRITCH, a citizen of the United States, residing at Watertown, Massachusetts, have invented a new, original, and ornamental Design for Tire-Treads, of which the following is a specification, reference being had to the accompanying drawing, forming a part thereof.

The figure is a face view of a portion of a tire showing my new design.

I claim:

The ornamental design for a tire tread as shown.

ELUE O. FRITCH.

Witnesses:

W. W. DUNCAN,
EMMA G. COLLINS.
